ART OF TANNING HIDES AND SKINS

Matthew M. Merritt, Middleton, Mass., assignor
to The Tanning Process Company, Boston,
Mass., a corporation of Massachusetts

Application January 24, 1931, Serial No. 511,026

17 Claims. (Cl. 149—4)

This invention relates to the art of treating hides, skins and leather. While the invention is illustrated with reference to apparatus for use in tanning operations upon hides and skins, it is 5 to be understood that the invention and various characteristics thereof may have other applications and uses.

Objects of the invention are to facilitate treatment of hides and skins in such manner that 10 certain preliminary operations by which the hides or skins are prepared for tanning may be so conducted as to simplify the operations connected with both the preparation of the hides and skins and the tanning thereof, and to reduce greatly 15 the handling of the hides and skins. Other objects of the invention are to speed up production and at the same time reduce the labor cost incidental to tanning operations.

To these ends and in accordance with an important characteristic of the invention a hide or skin is first slicked out upon a portable backing of such a nature that it will maintain the hide or skin fully extended while it is being treated. It is especially advantageous in tanning operations 25 to have the hide or skin slicked out in fully extended condition upon a portable backing since theslicking out operation causes the hide or skin to adhere to the portable backing to maintain the full normal area of the hide or skin while it is 30 undergoing treatment by a tanning material, a treatment which very frequently resulted in shrinkage of the hide or skin when carried out in accordance with methods commonly in use in the past. While the tanning material is acting on 35 the hide or skin maintained in fully extended condition by its backing, the hide or skin and its backing may be transferred as a unit to some other location or it may be stacked with other similarly treated units.

40 From another viewpoint the invention comprises spreading a hide or skin out upon a backing having flexible marginal portions, bending the marginal portions upwardly to convert the backing into a liquid container, and applying a treating liquid to the hide or skin while the latter is 45 maintained by its backing in its extended condition. In practising the method referred to in the foregoing sentence, a hide or skin is first spread out in extended condition upon a portable 50 backing after which a treating liquid is applied to the exposed surface of the hide or skin while the latter is maintained in its extended condition by its backing. Subsequently the hide or skin is reversed upon its backing to expose the other 55 surface, after which the flexible marginal por-

tions of the backing are bent upwardly to convert the backing into a container for liquid, and then more of the treating liquid is applied to the exposed surface of the hide or skin while the latter is still maintained in extended condition on its 60 backing.

From still another viewpoint the invention comprises subjecting a hide or skin while spread out upon a portable backing to treatment by a treating fluid and subsequently stacking the portable backing with its treated hide or skin with other similar backings having similarly treated hides or skins thereon. Not only is considerable space saved in the factory by thus stacking the 65 hides or skins and their portable backings but the 70 treating liquid may continue to act while the hides or skins and their backings are thus stacked. It is practical, for instance, to apply a tanning material to light skins while they are upon their 75 portable backings and to complete the tanning 80 while they and their backings are maintained in stacked relation. In the case of heavier hides or skins, each hide or skin may be removed from its 85 backing after it has set in extended condition due to partial tanning by the tanning material, and then be subjected to further tanning operations either in a vat or in a drum. Alternatively, the 90 hides or skins and their backings may be re-stacked, during which operation fresh tanning material is added to the exposed surface of each 95 hide or skin while the latter remains in extended condition on its backing.

It is to be understood that the method of tanning hides and skins herein disclosed is, in its broader aspects, disclosed and claimed in my 90 copending application, Serial No. 402,319, filed October 24, 1929.

For use in practicing the method described and claimed herein, there is provided a plurality of work supports or backing members each comprising a sheet of flexible material of a size suitable for the work to be handled and having marginal portions readily bendable above the level of the body portion thereof whereby each sheet may serve not only as a support for a hide or skin but as a container which will hold the desired amount of treating liquid applied to the hide or skin thereon. When stacked, or when placed individually on a proper support or table, for instance a table having raised marginal portions, the marginal portions of each work support are bent upwardly by said raised marginal portions so as to hold a certain amount of treating liquid in contact with the upper surface of the sheet and of the piece of work thereon. The lightness of 110

the work support, consisting as it does of a sheet of material without edge pieces or thickened portions, contributes to the facility with which it is moved about. I have found that sheets of linoleum, of rubber or rubberized fabric, and of Quaker felt possess all of the described advantages as backing members or work supports because of their lightness, and the readiness with which they may be caused to hold treating liquid as a 10 container.

These and other important characteristics of the invention will now be described in detail and then pointed out more particularly in the appended claims.

15 In the drawings,

Fig. 1 is a view in side elevation of an apparatus for use in the treating of hides and skins;

Fig. 2 is a plan view from above of Fig. 1, (on the line II—II of Fig. 1) with parts omitted, in 20 order to show to better advantage the sequence of operations upon the work;

Fig. 2a indicates a vat used in connection with the machine illustrated in Figs. 1 and 2;

Fig. 3 is a detail sectional view of a support for 25 the work;

Fig. 4 is a view similar to Fig. 1 illustrating a modification in the method of treating hides and skins;

Fig. 5 is a plan view from above, taken along the 30 line V—V of Fig. 4; and

Fig. 6 is a sectional view taken along the line VI—VI of Figs. 1 and 4.

The illustrated apparatus, which was designed 35 specially for the practice of the novel method of tanning herein described and claimed, forms the subject-matter of an application, Serial No. 643,577, filed Nov. 21, 1932 as a division of this application.

As shown, the apparatus embodies a conveyor 40 mechanism 10 (Figs. 1 and 2) comprising an endless belt conveyor 12 arranged to pass around two end rolls 14 and 16, the latter being driven through a sprocket wheel 18 which is fixed to shaft 20 of the roll 16. Passing around the sprocket wheel 18 45 is a chain 22 also passing around a second sprocket wheel 24 on a shaft 26 carrying a sprocket wheel 28. Passing around the sprocket wheel 28 is a chain 30 which also passes around a sprocket wheel 32 on the shaft of a motor 34 which serves 50 as a convenient source of power for moving the belt conveyor 12. The upper run of the belt conveyor 12 rests upon a smooth, flat table 36.

Since the belt conveyor 12 is relatively wide and 55 heavy and made of rubber, or of rubberized fabric, means is provided for lubricating the under side of the belt conveyor 12 and the upper surface of the table 36 to lessen friction and thereby facilitate the operation of the motor employed in moving the belt conveyor over the table. Conveniently water is used as the lubricating liquid. 60 For wetting the belt conveyor 12 and for discharging water upon the upper surface of the table 36, between such surface and the under side of the belt conveyor 12, there is provided in the illustrated construction a main pipe 40 from which there extends a number of branches, one of which is shown at 42 in Fig. 1 of the drawings. This branch pipe 42 has an upwardly extending 65 end piece 44, the mouth of which opens upon the upper surface of the table 36 below the upper run of the belt conveyor 12. Several of these branch pipes 42 are employed in the length of the table to insure proper lubrication between the table 36 and belt conveyor 12 when the table and belt are 70 relatively long as shown in Fig. 4, each branch

pipe 42 being provided with a valve 46 controllable by a hand wheel 48 so that the amount of water discharged may be regulated in accordance with the judgment of the operator. As shown most clearly in Fig. 6 the branch pipes 42 discharge upon the upper surface of the table 36 at points located substantially upon the longitudinal center line of the table.

For collecting and discharging the excess lubricating liquid there is provided at each edge of the table a trough 50 (Figs. 1 and 6), each trough being provided with a discharge pipe such as that shown at 52 (Fig. 6) which leads to a large discharge pipe 53 (Figs. 1 and 4). Preferably and as shown the discharge pipe 53, at its lower end is located above a large trough 56 which discharges into any convenient sewer through a pipe 58 (Fig. 4).

While the hides or skins are resting upon the upper surface of the belt conveyor 12 certain operations may be performed, such as that of slicking out each hide or skin whereby a considerable proportion of the watery content of each hide or skin is removed therefrom, and then applying tanning material to the slicked-out hide or skin. Means is provided for draining waste watery material, produced by the slicking-out operation, from the upper surface of the traveling belt conveyor, this means conveniently comprising, in the illustrated machine, the troughs 50 which, as stated, are utilized in the discharge of the excess lubricating liquid. By having the trough under the longitudinal edges of the belt conveyor 12, the latter overhangs at its edges the said troughs 50 and readily discharges into the troughs the waste material from the hides and skins. Hence the troughs 50 and the connected pipes 52 discharge not only excess lubricating liquid but the waste material from the hides and skins.

As most clearly shown in Figs. 1 and 4 of the 15 drawings the lower run of the belt conveyor is relatively slack and is carried by a plurality of rollers 60. Between two adjacent rollers 60 there is located a small tank 62 containing water, the arrangement being such that the lower run of the 20 belt conveyor dips down into this tank of water and is washed on both of its surfaces as it passes lengthwise of the tank. The tank 62 is conveniently supplied with water by means of a branch pipe 64 extending from the main pipe 40 of the water lubricating system, a valve 66 being provided in the pipe 64 for controlling the supply of water to the tank 62. The main pipe 40 of the water lubricating system may be attached to the water supply pipe of the factory in which 130 the machine is located.

At the entering end of the belt conveyor 12 there is provided a feeding-in table 70 (Fig. 1) up which pieces of work may be shoved for engagement with the belt conveyor 12. While on this table, tanning material may be applied to the work by a worker standing on a platform 73. Conveniently, and as shown, each piece of work, whether a hide or skin, is placed upon a portable backing or work support 71, a stack of such backing members or work supports being shown at 72 resting upon the supporting surface of a table truck 74. At the discharge end of the belt conveyor 12 there is provided a discharging table 75 consisting of a number of slats having beveled 145 end portions located closely adjacent to the belt conveyor 12 where it starts downwardly around the roll 16 so as to take each portable backing member or work support 71 from the conveyor as it reaches this point in its travel. A workman 150

will remove each backing member or work support with the work thereon from the discharge table 75 and place it upon the supporting surface of a table truck 76 having a specially constructed 5 supporting surface as will hereinafter be described.

Mounted above the conveyor mechanism 10 is a tank 80 (Fig. 4) for holding the desired tanning solution, a gage being conveniently provided at 10 one or both ends of the tank 80 to indicate the quantity of solution therein, the said gage comprising a transparent tube 81 connected with the tank and an indicator scale 83 which may be of a construction old and well known in the industry. 15 From the tank 80 a pipe leads to a main 82 to which is connected a number of flexible discharge tubes 84 and 86 (Fig. 1), the lower portions of which may be freely moved to discharge a treating liquid on the moving work, each discharge 20 tube having a hand operated valve 85 so that the operator may control the amount of tanning liquid to be discharged therefrom upon any given piece of work.

Located adjacent to the table truck 74 at the 25 entering end of the conveyor mechanism is a table truck 90 (Figs. 1 and 2) adapted to receive a stack of hides or skins 92 from any suitable source, to transfer them to a location adjacent to the table truck 74 and to hold or support them in 30 such location that the hides or skins may be transferred one at a time to a work treating station on the stack of work supports 71. Subsequently the hide or skin is shifted to another station below the tube 84.

35 Located adjacent to the table truck 76 at the discharge end of the conveyor mechanism is a vat 94 (Fig. 2) also made in the form of a truck so that it may be readily transferable from one location to another.

40 For convenience in operating upon the hides or skins there will be provided, as already stated, a plurality of portable backing members or work supports 71 shown in stack formation at 72 in Fig. 1. These backing members or work supports 45 are in the form of mats or sheets without border pieces or thickened portions. Each mat or sheet is substantially the same thickness throughout and is flexible, at least in its marginal portions, so that these portions are readily bendable upwardly above the plane of the body portion of the mat or sheet to form a container whereby the sheet may be readily transformed 50 from a plane work supporting sheet to a container and vice versa.

55 When it is desired that the sheets shall serve as containers it is necessary only to place them upon a table truck like that shown at 76 the upper surface of which, as most clearly shown in Fig. 3 has marginal members 100 raised above the flat 60 top 102 of the table truck. As shown in Fig. 3, a sheet or mat or backing member 71 placed on the table top 102 will conform more or less to the table top and to the marginal members 100 so that the marginal portions of the sheet or mat 65 are bent upwardly, thus converting the sheet into a container whereby any liquid or liquids applied to the hide or skin on the sheet or mat will not escape by draining therefrom. The work supports 71 which, as stated, are in the form of sheets 70 or mats, should be light to be readily portable and should also be of material readily "wetted" by water, as will be hereinafter explained. Examples of substances which have these desired qualities are rubber or rubberized fabric, linoleum and Quaker felt. This last-mentioned sub-

stance, namely, Quaker felt, is made of sheets of felt impregnated with asphaltum and having surfaces finished with a flexible paint or enamel.

As stated above, the mat or sheet should be of material which is readily wetted by water, that is, it should be water-adherent so that a hide or skin slicked-out on one of its surfaces will adhere thereto to a considerable degree. Moreover, if the stack of mats or sheets at 71 have their surfaces wet with water as they are stacked up on the table truck 74, they will readily be drawn up on to the belt conveyor 12, which also has a water-adherent surface, when a foot or more of one end of the mat or sheet has been engaged with the wet surface of the belt conveyor 12 passing around the roller 14. Because of this fact the workmen who stand on the opposite sides of the table truck 74 need not transfer each work support 71 into full engagement with the belt conveyor 12, it being necessary only to shove each work support in turn up the slanting feeding-in table 70 until the forward end of the given work support 71 is engaged with the traveling belt conveyor 12 since in that case the light work support will be drawn onto the belt conveyor 12 and will pass along the conveyor 10 mechanism 10 in a position to have the work treated by other workmen who stand on platforms 95 on opposite sides of the conveyor mechanism 10.

While certain advantages of the backing members or work supports 71 have been pointed out in the foregoing paragraph, the principal advantage of utilizing a light and readily portable work support of the type herein disclosed resides in the fact that a hide or skin may be stretched out or 105 slicked-out upon a surface of such a backing or work support and then subjected to treatment at different stations and transported and stacked, if desired, while it remains in spread out or slicked-out condition on its work support. In other words, the work support becomes a backing or 110 temporary stiffening for the work and may be handled and treated as part of the work. While the hide or skin is in fully extended or slicked-out condition on the backing or work support it 115 is subjected to treatment by a tanning solution and then with its work support is removed from the table or bench where the work was done so that the operator or operators at said bench or 120 table may continue operations on other pieces of work while the backing or work support with its treated hide or skin is being carried off by a conveyor or other suitable means or stacked with other backings or work supports having similarly 125 treated hides or skins thereon. All the time that the work support with its treated hide or skin 130 is being moved by conveyor or otherwise or while it is in stacked relation to other similar work supports, the tanning material is acting on the hide or skin substance. If a long conveyor be 135 provided, such as that shown in Fig. 4 of the drawings, the tanning material may have acted for a sufficient length of time when the hide or skin with its backing or work support reaches the other end of the conveyor, so that the hide or skin, now partially tanned or set in its extended condition, may be removed at once from its backing or support and subjected to other operations intended to complete the tanning of that particular hide or skin. Where a relatively short 140 conveyor is used, like that shown in Fig. 1 of the drawings, the backing or work support with its treated hide or skin will be stacked with other similar backings or work supports having similarly 145 treated hides or skins thereon. While the 150

skins are stacked the tanning material continues to act, restriction of evaporation by the backings serving to keep the tanning material in condition to permeate the skins and become uniformly distributed therein. In this way, space is conserved since the portable work supports take up relatively little space as compared with benches or stationary work supports at which the operators must perform their work. Furthermore, time is saved in that the workers can remain at one station while the work is brought to them and removed again with little effort on their part. Again the tanning material continues to act while the backing or work support with its treated hide or skin is being moved to the desired location for stacking or for removal of the hide or skin from backing or its work support.

In treating hides and skins with the apparatus disclosed in Figs. 1 to 3, inclusive, of the drawings, a stack of hides or skins 92 is placed upon the table truck 90 and the latter is located adjacent to the table truck 74 upon which a stack of backing members or work support 71 has been placed with both surfaces of each work support moistened with water. A hide or skin is transferred from the stack of the table 90 to the exposed surface of the top work support 71 of the stack 72. On this top work support a piece of work if it be a heavy hide is spread out in substantially extended condition with all folds and wrinkles effaced. Hides are subjected to a putting-out operation before reaching the table 90. Each hide is then treated on its grain surface with a tanning solution obtained from the flexible tube 84 through proper manipulation of the valve 85 adjacent to the lower end of the tube. If the piece of work be a skin or light hide, it will be slicked out in fully extended condition while resting on the top work support of the stack 72 and before the application of tanning material through tube 84. It will be understood that the workers at this station may make use of brushes or swabs to spread the tanning liquid substantially uniformly over the exposed grain surface of the hide or skin. However, it is preferred to have this done at another station, viz., at the feeding-in table 70. The use of spraying devices for applying tanning material to the hides or skins is also contemplated. As soon as the application of tanning material has been accomplished, the work support with its treated hide or skin is shoved up the feeding-in table 70 until its forward end engages with the traveling belt conveyor 12, the upper surface of which is wet with water as above described. The work support 71 travels with the belt conveyor 12 and is soon in a position to be operated by workers, standing one on each side of the conveyor mechanism 10, who spread out the hide or skin after having reversed it by placing the grain surface down upon its backing or work support 71. Care is taken to do a thorough job of slicking-out on skins so that the latter may be extended to their full normal area upon the upper surface of the backing or work support 71. In performing this slicking-out operation a large proportion of the watery content of the skin, including some of the spent tanning solution, is removed therefrom and subsequently drains into the troughs at each side of the belt conveyor 12. After the slicking-out operation, which is performed while the work support 71 and the hide or skin thereon are traveling along with the belt conveyor 12, the latter discharges the work support 71 with its slicked-out hide or skin on to the discharge table 75 from which it is

removed by a worker and placed upon the table truck 76. When placed upon this table truck 76 the marginal portions of the backing or work support 71 bend upwardly for reasons given above, thus converting the plane sheet work support 71 into a container. As soon as the work support or backing 71 with its slicked-out hide or skin has been placed upon the table truck 76, strong or concentrated tanning solution, obtained from the tube 88 by proper manipulation of the valve 85 is applied to the hide or skin, the tanning liquid being spread over the exposed flesh surface of the hide or skin in a uniform manner with the aid of a brush or a swab. Preferably the tanning solution is allowed to act upon the fully stretched out hide or skin for a time substantially just sufficient to set the hide or skin in its fully extended condition. This means that the hide or skin is only partially tanned on the work support 71, but to such an extent that it will subsequently maintain this area while it is undergoing other operations intended to complete the tanning thereof. Conveniently each work support 71 with its slicked-out skin which arrives at the discharge table 75 will be placed upon the work support 71 which preceded it, and the hide or skin thereon treated as just described. In this way, the work supports 71 with their treated hides or skins are stacked up on the table truck 76 to a convenient height whereupon this table truck may be readily shoved to one side and an empty one substituted therefor. After the hides or skins have been left in the stack on the table truck 76 for a sufficient length of time, which may be as short as fifteen minutes in the case of very thin skins but which may be for a period of hours and even over night, each hide or skin is removed in turn from its work support and placed in a body of tanning solution such as that contained in the portable vat shown at 94 in Fig. 2a. This portable vat 115 contains a quantity of the desired tanning solution, and as each hide or skin is placed therein both of its surfaces are thoroughly wetted with the tanning solution. Hides or skins thus placed individually in the solution in the vat 94 do not become closely packed together but are separated by a substantial film of tanning solution. The tanning is readily finished in this vat with the hides or skins in fully extended condition. After the requisite length of time they are removed and finished in accordance with any of the old and well-known methods commonly employed in leather manufacturing establishments. While it is preferred with certain kinds of leather designed for certain purpose to finish the tanning in vats similar to that shown at 94, for certain other purposes the hides or skins, and particularly hides intended for sole leather, may be finished by drumming with a strong or concentrated solution of tanning material. Drumming hastens the penetration of the tanning solution and, in the case of hides, loading of the hide with tanning material may be more readily accomplished than in a vat.

In the modification shown in Figs. 4 and 5, the hides or skins are not treated upon individual work supports. Hence a table truck 110, located at the entering end of a belt conveyor 112, will have hides or skins 114 stacked thereon. Since the work of slicking-out and applying tanning solution to the hides and skins will be carried out while the hides or skins are traveling along with the upper run of the belt conveyor 112, the latter is made considerably longer than the corresponding belt conveyor 12 of Fig. 1. Otherwise

the belt conveyor mechanism of Fig. 4 may be similar in all respects to that shown in Fig. 1. At the discharge end of the belt conveyor 112 there is provided a vat truck 116 similar to that shown 5 at 94 in Fig. 2 of the drawings.

In operating the apparatus disclosed in Figs. 4 and 5 for the treatment of hides and skins, a stack of hides or skins 114 is placed upon the table truck 110. In case heavy hides are being 10 treated, they will be subjected to a putting-out operation in a machine provided for that purpose, before being placed upon the table truck 110. The top hide or skin with its grain surface facing upwardly is treated, while spread out to expose all portions of its grain surface, with 15 tanning solution obtained from a flexible tube 118 through proper manipulation of the valve 120. This hide or skin is at once transferred by the worker to the belt conveyor 112. The worker 20 or workers at the conveyor mechanism at once reverse this hide or skin, placing the grain surface down upon the belt conveyor 112. Here, the piece of work, if it is a skin or light hide, is thoroughly slicked-out in fully extended condition 25 while being carried along on the conveyor, the slicking-out operation also removing a large proportion, approximately one-half, and, in some cases, the larger portion, of the watery contents of the hide or skin. A heavy hide is spread out in 30 fully extended condition with the grain surface down. Following this operation another worker will treat the exposed flesh surface of the hide or skin with tanning solution from a flexible tube 122, a brush or swab being made use of to spread 35 the tanning solution uniformly over the flesh surface of the slicked-out hide or skin. The belt conveyor 112 is so long and moves at such a speed that several minutes will elapse from the application of tanning solution through the tube 122 40 until such treated hide or skin reaches the discharge end of the belt conveyor 112. During this travel light hides and skins are partially tanned so that they may be removed by a worker without danger of losing their slicked-out area and immediately placed in a body of strong or concentrated 45 tanning solution in the vat 114, care being taken to see that the hide or skin is spread out in its fully extended condition in the vat. In case the 50 hides or skins are of considerable thickness they may be stacked upon a table similar to the table truck 76 of Figs. 1 and 3, where they will be allowed to remain until the tanning solution has struck into the hide or skin substance sufficiently to give a set to the fibers thereof such that they 55 will not subsequently shrink when introduced into a vat or drum for the completion of the tanning operation. Here, again, the hides or skins may be drummed after they have been allowed to set for the required length of time. It is clear 60 from the foregoing description, that the traveling belt conveyor 112 serves as a portable backing for one or for a number of skins at the same time, and that the improved method of treating 65 hides and skins, as defined in the broader of the claims hereto appended, may be practiced with the aid of a belt conveyor similar to that designated 112 in the accompanying drawings.

Having described my invention, what I claim as new and desire to secure by Letters Patent of 70 the United States is:

1. That improvement in methods of tanning hides and skins which comprises spreading out a hide or skin in fully extended condition on a portable backing which will maintain the hide or skin 75 fully extended, treating the hide or skin with

tanning material while it is maintained extended on said backing, and stacking the treated hide or skin, still spread out on said backing, in contact above and below with other similarly treated hides or skins on their backings to continue the tanning of the hides or skins in the stack. 80

2. That improvement in methods of tanning hides and skins which comprisesslicking out a hide or skin on a portable backing which will maintain the hide or skin in fully slicked-out condition, subjecting the hide or skin to treatment by a tanning material while it is maintained extended on said backing, and stacking the treated hide or skin, still spread out on its backing, in contact above and below with other similarly treated hides and skins and their backings to continue the tanning of the hides or skins in the stack. 85

3. That improvement in methods of treating hides and skins which comprises slicking a hide or skin out in fully extended condition upon a portable work support, applying a tanning solution to the exposed surface of the hide or skin on the work support, reversing the hide or skin on its work support and slicking it out again in fully 90 extended condition on the portable work support and simultaneously therewith removing a large proportion of the water content of the hide or skin, and applying a tanning solution to the slicked-out hide or skin to complete the tanning 100 thereof. 95

4. That improvement in methods of treating hides and skins which comprises subjecting a hide or skin spread out in extended condition upon a portable work support to treatment by a tanning 110 solution, transferring the portable work support with the treated hide or skin thereon to a station for further treatment, slicking the hide or skin out in fully extended condition on the portable work support, transferring the portable work 115 support with the slicked-out hide or skin thereon to another station, applying a tanning solution to the slicked-out hide or skin, then removing the hide or skin from its portable work support, and placing the hide or skin in a body of strong 120 or concentrated tanning solution to complete the tanning thereof. 120

5. That improvement in methods of treating hides and skins which comprises spreading a hide or skin out in extended condition upon a portable 125 work support, applying a tanning solution to the exposed surface of the hide or skin on the work support, transferring the portable work support with the treated hide or skin thereon to a station for further treatment, slicking the hide or 130 skin out in fully extended condition on the portable work support and simultaneously therewith removing a large proportion of the water content of the hide or skin, transferring the portable work 135 support with the slicked-out hide or skin thereon to another station and applying a tanning solution to the slicked-out hide or skin, stacking a number of the portable work supports with the treated hides or skins thereon, and permitting the tanning solution to act for a time sufficient to set 140 the fibers of each hide or skin before removal of the hides or skins from their work supports. 140

6. That improvement in methods of treating hides and skins which comprises spreading a hide or skin out in extended condition upon a portable 145 work support, applying a tanning solution to the exposed surface of the hide or skin on the work support, transferring the portable work support with the treated hide or skin thereon to a station for further treatment, slicking the hide or skin 150

out in fully extended condition on the portable work support and simultaneously therewith removing a large proportion of the water content of the hide or skin, transferring the portable work support with the slicked-out hide or skin thereon to another station and applying a tanning solution to the slicked-out hide or skin, stacking a number of the portable work supports with the treated hides or skins thereon to permit the tanning solution to act for a time sufficient to set the fibers of the hide or skin in each case before removal of the hides or skins from their work supports, removing the hides or skins from their work supports after the hides or skins have had time to set each in its extended condition, and placing the hides and skins freshly removed from their work supports in a body of tanning liquid to complete the tanning thereof.

7. That improvement in methods of treating hides and skins which comprises spreading a hide or skin out in extended condition upon a portable work support, applying a tanning solution to the exposed surface of the hide or skin on the work support, transferring the portable work support with the treated hide or skin thereon to a station for further treatment,slicking the hide or skin out in fully extended condition on the portable work support and simultaneously therewith removing a large proportion of the water content of the hide or skin, transferring the portable work support with the slicked-out hide or skin thereon to another station and applying a tanning solution to the slicked-out hide or skin, stacking a number of the portable work supports with the treated hides or skins thereon to permit the tanning solution to act for a time sufficient to set the fibers of the hide or skin in each case before removal of the hides or skins from their work supports, removing the hides or skins from their work supports after the hides or skins have had time to set each in its extended condition, and placing the hides or skins individually in a body of tanning liquid to complete the tanning thereof.

8. That improvement in methods of treating hides and skins which comprises spreading a hide or skin out in extended condition upon a portable work support, applying a tanning solution to the exposed surface of the hide or skin on the work support, transferring the portable work support with the treated hide or skin thereon to a station for further treatment,slicking the hide or skin out in fully extended condition on the portable work support and simultaneously therewith removing a large proportion of the water content of the hide or skin, transferring the portable work support with the slicked-out hide or skin thereon to another station and applying a tanning solution to the slicked-out hide or skin, stacking a number of the portable work supports with the treated hides or skins thereon to permit the tanning solution to act for a time sufficient to set the fibers of the hide or skin in each case before removal of the hides or skins from their work supports, removing the hides or skins from their work supports after the hides or skins have had time to set each in its extended condition, and drumming the hides or skins in a strong tanning solution to complete the tanning thereof.

9. That improvement in methods of tanning hides or skins which comprises applying a tanning liquid to a series of hides or skins spread out each upon an individual portable backing,

stacking the portable backings with their treated hides or skins with each hide or skin between and in contact with two backings, and maintaining them stacked for at least a part of the time during which the tanning liquid continues to act.

80

10. That improvement in methods of tanning hides and skins which comprises slicking a hide or skin out in fully extended condition upon a portable work support, applying tanning material to the slicked out hide or skin while at a given station, removing the portable work support and the treated hide or skin thereon from said station, permitting the treated hide or skin to remain on the portable work support until it is partially tanned in its spread-out condition, and then placing the hide or skin in a body of tanning solution to complete the tanning operation.

85

11. That improvement in methods of treating hides and skins which comprises treating a hide or skin spread out in extended condition upon a portable work support with a tanning solution, stacking a number of the portable work supports with the treated hides or skins thereon to permit the tanning solution to act for a time sufficient to set the fibers of each hide or skin before removal of the hides or skins from their work supports, removing the hides or skins from their work supports after the hides or skins have had time to set each in its extended condition, and subjecting the hides or skins to treatment by a tanning solution to complete the tanning thereof.

90

12. That improvement in methods of treating hides and skins which comprises treating a hide or skin spread out in extended condition upon a portable work support with a tanning solution, stacking a number of the portable work supports with the treated hides and skins thereon to permit the tanning solution to act for a time sufficient to set the fibers of each hide or skin before removal of the hides or skins from their work supports, removing the hides or skins from their work supports after the hides or skins have had time to set each in its extended condition, and placing each hide or skin individually in a body of tanning liquid in fully extended condition so that both surfaces of the hide or skin are thoroughly wetted by the tanning solution.

105

13. That improvement in methods of treating hides and skins which comprises treating a hide or skin spread out in extended condition upon a portable work support with a tanning solution, stacking a number of the portable work supports with the treated hides or skins thereon to permit the tanning solution to act for a time sufficient to set the fibers of each hide or skin before removal of the hides or skins from their work supports, removing the hides or skins from their work supports after the hides or skins have had time to set each in its extended condition, and drumming the hides or skins in a strong or concentrated tanning solution to complete the tanning thereof.

110

14. That improvement in methods of treating hides and skins which comprises spreading out a hide or skin in fully extended condition upon a portable backing having flexible marginal portions, said spreading operation being performed while the portable backing is supported in flat condition, applying a treating liquid to the exposed surface of the hide or skin, reversing the hide or skin upon its portable backing, bending up the marginal portions of the backing and, while said marginal portions are bent upwardly, 145

- applying a larger quantity of treating liquid to the exposed surface of the hide or skin.
15. That improvement in methods of tanning hides and skins which comprisesslicking out a hide or skin upon a portable backing having flexible marginal portions, said slicking operation being performed while the portable backing is supported in flat condition, applying a tanning liquid to the exposed surface of the hide or skin, 10 reversing the hide or skin upon its portable backing, bending up the marginal portions of the backing and, while said marginal portions are bent upwardly, applying a larger quantity of tanning liquid to the exposed surface of the hide or 15 skin.
16. That improvement in methods of tanning hides or skins which comprises spreading a hide or skin out in fully extended condition on a sheet of flexible material while the latter is supported 20 in flat condition, applying a tanning liquid to the exposed surface of the hide or skin while the marginal portions of the sheet of material are

maintained bent upwardly to prevent for the desired length of time the escape of any liquid, and stacking the sheet of material with its treated hide or skin with other similar sheets and skins.

17. That improvement in methods of tanning hides or skins which comprises slicking a hide or skin out in fully extended condition on a sheet of flexible material while the latter is supported in flat condition, bending the marginal portions of the sheet of material upwardly to form a container adapted to prevent the escape of liquid, then applying a tanning liquid to the exposed surface of the hide or skin on said sheet of material, stacking the sheet of material with its treated hide or skin with other similar sheets and skins and with said marginal portions of the sheets in bent up condition to retain the tanning liquid, and permitting the tanning liquid to act on the stacked hides or skins for the desired length of time.
